(57) **CLAIM**

The ornamental design for a luminaire, as shown and described.

DESCRIPTION

FIG. 1 is a bottom perspective view of a luminaire showing a first variant of the design;

FIG. 2 is a front view thereof;

FIG. 3 is a side view thereof;

FIG. 4 is a top view thereof;

FIG. 5 is a bottom view thereof;

FIG. 6 is a bottom perspective view of a luminaire showing a second variant of the design;

FIG. 7 is a front view thereof;

FIG. 8 is a side view thereof;

FIG. 9 is a top view thereof;

FIG. 10 is a bottom view thereof;

FIG. 11 is a bottom perspective view of a luminaire showing a third variant of the design;

FIG. 12 is a front view thereof;

FIG. 13 is a side view thereof;

FIG. 14 is a top view thereof;

FIG. 15 is a bottom view thereof;

FIG. 16 is a bottom perspective view of a luminaire showing a fourth variant of the design;

FIG. 17 is a front view thereof;

FIG. 18 is a side view thereof;

FIG. 19 is a top view thereof;

FIG. 20 is a bottom view thereof;

FIG. 21 is a bottom perspective view of a luminaire showing a fifth variant of the design;

FIG. 22 is a front view thereof;

FIG. 23 is a side view thereof;

FIG. 24 is a top view thereof;

FIG. 25 is a bottom view thereof;

FIG. 26 is a bottom perspective view of a luminaire showing a sixth variant of the design;

FIG. 27 is a front view thereof;

FIG. 28 is a side view thereof;

FIG. 29 is a top view thereof;

(Continued)

FIG. 30 is a bottom view thereof;
FIG. 31 is a bottom perspective view of a luminaire showing a seventh variant of the design;
FIG. 32 is a front view thereof;
FIG. 33 is a side view thereof;
FIG. 34 is a top view thereof;
FIG. 35 is a bottom view thereof;
FIG. 36 is a bottom perspective view of a luminaire showing an eighth variant of the design;
FIG. 37 is a front view thereof;
FIG. 38 is a side view thereof;
FIG. 39 is a top view thereof; and,
FIG. 40 is a bottom view thereof.
The portions of the luminaire shown in broken lines form no part of the design. The thin diagonal lines indicate translucency.
